[57] ABSTRACT

The present invention relates to a nectarine tree and more particularly to a new and distinct variety broadly characterized by a medium size, medium vigor, hardy, very productive and regular bearing tree. The fruit matures under the ecological conditions described approximately the second week in July, with first picking on July 9, 1988. The fruit is uniformly large in size, clingstone in type, very firm making excellent quality for keeping and shipping, deep red over a reddish orange background in skin color, and both acidic and very sweet in flavor. The variety was developed as the result of a second generation seedling from the selected seed parent, Red Diamond (U.S. Pat. No. P.P. 3,165, and an unnamed nectarine seedling as the selected pollen parent.

1 Drawing Sheet

1

BACKGROUND OF THE VARIETY

In a continuing effort to improve the quality of shipping fruits, we, the inventors, typically hybridize a large number of nectarine, peach, plum, apricot, and cherry seedlings each year. The present invention relates to a new and distinct variety of nectarine tree, which has been denominated varietally as "Summer Bright". The present variety was hybridized in 1981 by us in a cultivated area of our experimental orchard at Bradford Farms near Le Grand, Calif. in Merced County (San Joaquin Valley). It was the result of a second generation seedling of Red Diamond (U.S. Pat. No. P.P. 3,165) as the selected seed parent and an unnamed seedling as the selected pollen parent. Subsequent to origination of the present variety of nectarine tree, we asexually reproduced it by budding and grafting, and such reproduction of plant and fruit characteristics were true to the original plant in all respects.

The fruit produced by the present variety most nearly resembles the fruit of Summer Diamond (U.S. Pat. No. P.P. 5,654) by being a nearly full red colored nectarine with excellent firmness, but is distinguished therefrom and an improvement thereon by harvesting 5 days earlier, by being a clingstone instead of a freestone, and by being much sweeter in flavor.

The present variety is similar to its selected seed grandparent, Red Diamond (U.S. Pat. No. P.P. 3,165), in fruit appearance by being a nearly full red colored nectarine with excellent firmness, but is distinguished therefrom by ripening 18 days later and by being a clingstone instead of a freestone.

DRAWING

The accompanying photograph shows the characteristics of the whole fruit in skin color and form, a characteristic fruit divided near its suture plane showing the flesh and pit cavity, a typical stone, and typical leaves.

POMOLOGICAL CHARACTERISTICS

Referring now more specifically to the pomological characteristics of this new and distinct variety of nectarine tree, the following has been observed under the

2

ecological conditions prevailing near Le Grand, Merced County (San Joaquin Valley), Calif., and was developed at the state of hard ripe on July 14, 1988. All major color code designations are by reference to the International Society Color Council, National Bureau of Standards. Common color names are also used occasionally.

TREE

10 Size: Medium.

Vigor: Medium.

Growth: Spreading and dense.

Form: Vase formed.

Hardiness: Hardy.

15 Production: Very productive.

Bearing: Regular bearer.

Trunk:

Size.—Medium.

Texture.—Medium.

Color.—Grayish yellowish brown [80. gy.yBr].

Lenticels.—Numerous. Color: Strong brown [55. s.Br]. Average Size: $\frac{1}{8}$ " to $\frac{1}{4}$ ", [3.175–9.525 mm.].

20 Branches:

Size.—Medium.

Texture.—Medium.

Color.—1st year wood — Topside: Dark pink [6. d.Pk] in sunlight. 1st year wood — Underside: Brilliant yellow green [116. brill.YG]. Older wood: Grayish brown [61. gy.Br].

Lenticels.—Numerous, very small.

25 Leaves:

Size.—Large. Average length: 6.0" [152.4 mm.]. Average width: 1 9/16" [39.69 mm.].

Thickness.—Medium.

Form.—Elliptical.

Apex.—Acuminate.

Base.—Acute.

Surface.—Smooth.

Color.—Dorsal surface: Moderate olive green [125. m.01G]. Ventral Surface: Moderate yellow green [120. m.YG].
